CONTROL DEVICE FOR TURNTABLES

John J. Shively, New York, N. Y.

Application March 2, 1944, Serial No. 524,764

4 Claims. (Cl. 192—124)

1

The present invention pertains to improvements in control devices.

In Patent No. 2,261,420 and Application Serial No. 383,904, filed March 18, 1941, now Patent Number 2,340,147, are described and claimed telephone answering and recording devices in which the various functions are controlled cyclically by a cooperative group of cams and switches.

An object of the present invention is to provide improved means to carry out a cyclic operation of the above or similar nature with complete precision control of the starting and stopping position of the various cams and related elements.

Another object is to provide means of the above type in which the cyclic controls are operable by an electric motor, but in which the starting and stop positions of the control elements are fixed independently of "coast" of the motor during the latter's stopping period.

A further object is to provide means of the above characteristics in which releasing clutches, and the like, are eliminated.

A further object is to provide means of the above type in which a gradual braking effect is applied to the motor to shorten the latter's coasting period.

Another object is to provide means of the above type in which the torque transmission between the motor and control elements is limited, whereby both are protected against injury in case of any interference with operation of the control elements.

A still further object is to provide apparatus of the above nature which is simple, cheap, and easily manufactured.

Other objects and advantages of the invention will become evident during the course of the following description in connection with the accompanying drawings, in which

Figure 1 is a longitudinal view taken partly in section through the plane of the worm and turntable shaft axis;

Figure 2 is a longitudinal view in section in the plane of the control shaft;

Figure 3 is a front elevation;

Figure 4 is a rear view of the rear cam and stop pin; and

Figure 5 is an electrical diagram illustrating typical connections of the motor, release solenoid and their respective switches.

Referring to Figure 1, the numeral 10 denotes a vertical shaft journaled in a casing 11 and carrying a worm 12 meshing with a worm-wheel 13. A record turntable 14 is secured on the upper end of the shaft 10 and is adapted to be

2

rim-driven by a motor 15, Figure 3, via a resilient idler pulley or roller 16. As the details of such roller drives are well known in the art and form, in themselves, no part of the present invention, no further description is necessary herein.

Referring to Figure 2, the worm-wheel 13 is secured to a sleeve 17 journaled in the casing 11. A horizontal shaft 18 is rotatably mounted in the sleeve 17. Secured on the front end of the shaft 18 is a flanged hub 19 carrying a plurality of cams 20, 20^a, 20^b, 20^c and 20^d. Obviously, the cams can be made in a single piece, but in the present embodiment they are made individually, preferably as stampings, spaced apart by phenolic washers 21 and all secured to the flanged hub 19 by bolts 22. The cams 20, 20^a, etc. are adapted to control switches 23, 23^a, 23^b, 23^c, and 23^d of any suitable type, herein illustrated as the type well known in the art as "microswitches."

The rear end of the sleeve 17 carries a driving flange 24. A driven disc 25 is secured to the rear end of the shaft 18, and a resilient friction washer 26, preferably of spring bronze or the like, is disposed in compression between the driving flange 24 and the driven disc 25. A small pin 27 is fixed in and protrudes from the rear face 28 of the disc 25. The disc 25 may have peripheral cam surfaces 29 and 30 engaging tappet levers 31 and 32, Figure 1, these levers being adapted to perform any desired functions in the device to be controlled by the present invention and being shown herein for purposes of illustration.

The main casing 11 is secured to an upper supporting plate 33, from which also depends a bracket 34 carrying a solenoid 35. A flat bell-crank 36 is pivoted to the bracket 34, the horizontal arm 37 of the crank being articulated to the plunger 38 of the solenoid 35. When the solenoid is deenergized, as in Figure 1, the relatively vertical arm 39 of the bell-crank 36 rides against the rear face 28 of the driven disc 25 and is adapted to be laterally engaged by the pin 27, thus acting as a detent.

Figure 5 illustrates typical electrical connections by which the cyclic operations of a device embodying the invention may be controlled. Referring to that figure, numerals 40 and 41 denote conductors of a source of current. A multiple contact relay 42 is connected on one side via a wire 43, a momentary contact switch 44 and a wire 45 to the supply conductor 40. The other side of relay 42 is connected via wires 46 and 47 and cam switch 23^b with the second supply conductor 41. The switch 23^b is normally held closed by the notched cam 20^b, the apparatus being

illustrated in normal or stop position of the cyclic operation.

One normally open contact 48 of the relay 42 is connected on one side to the wire 43 and on the other via leads 49 and 50 to the conductor 40. The lead 50 is also connected to one side of the normally open cam switch 23^a, the latter being controllable by the notched cam 20^a. The other side of switch 23^a is connected via leads 51 and 52 to a second normally open contactor 53 of relay 42, thence via a wire 54 to the conductor 40.

The lead 52 is also connected to the motor 15 and the solenoid 35. The motor 15 has a return connection 55 to conductor 41, while solenoid 35 normally has a return connection to conductor 41 via leads 56, 57, and the normally closed cam switch 23. It will be noted that the cam 20 has a short lobe 58 adapted to hold the switch 23 closed only in a short arc of revolution including stop position and a short rotary travel from that position. It will also be noted that the cam 20^a has a short notch 59 which allows the switch 23^a to open near the end of a cyclic operation and just prior to closure of switch 23 by cam lobe 58.

The relay 42 may have any desired number and character of contacts for controlling various circuits of the device requiring cyclic operation, such as the telephone recording devices previously referred to. Similarly, the cam switches 23^c and 23^d may control any desired circuits, being included herein to illustrate the fact that the present invention is applicable to any required number and combination of cyclic circuit control means.

A typical operation is as follows:

When the switch 44 is momentarily closed, either manually or by any suitable relay means, the relay 42 is energized through its connections previously described. As relay 42 closes, its contactor 48 completes a holding circuit from conductor 40 via leads 50 and 49 to wire 43, this circuit being parallel to switch 44 and therefore adapted to hold the relay energized when the switch 44 is opened.

Closure of relay 42 also completes a circuit from conductor 40 via lead 54, contactor 53 and lead 52 to the motor 15, thence through return lead 55 to supply conductor 41. At the same time the solenoid 35 receives current via lead 52, the solenoid circuit being completed through leads 56, 57 and cam switch 23.

As the motor 15 starts, it drives the turn-table 14, Figures 1, 2 and 3, and through the latter the shaft 10, worm 12, worm-gear 13, sleeve 17, and driving flange 24. As the solenoid 35 is energized, it raises the plunger 38, withdrawing the bell-crank detent 39 from the stop-pin 27 and allowing the disc 25 to be rotated. The driving hub 24 drives the disc 25 through the medium of the friction washer 26, thus revolving the shaft 18 and its attached cams.

Referring to Figure 5, when the cam 20 has been rotated a few degrees in the cyclic or clockwise direction, the lobe 58 allows switch 23 to open, deenergizing the solenoid 35. This allows the plunger 38 to drop, carrying the detent 39 again against the disc 25 as shown, but as the pin 27 has been moved forward past the detent 39, the cam assembly continues to revolve without interference throughout the cycle.

Near the end of one complete revolution the cam 20^b allows the switch 23^b to open momentarily, breaking the return connection from relay 42 to conductor 41 and causing the relay 42 to open. However, the cam 20^a holds the switch 23^a closed

at this point, thus maintaining the motor circuit independently of the relay 42. Shortly thereafter the notch 59 in cam 20^a allows the switch 23^a to open, deenergizing the motor 15. 5 Immediately thereafter the pin 27, carried by the momentum of the motor 15 and other rotating parts, engages the bell-crank arm 39 and is stopped thereby, causing the entire cam assembly to be stopped accurately in normal position. 10 Meanwhile, the friction washer 26 allows the driving disc 24, worm gearing, shaft 10 and motor 15 to revolve until their momentum is absorbed, thus avoiding any sudden shock to these parts.

The washer 26 is so proportioned that its frictional effect is sufficient to prevent rotary slip between the driving flange 24 and driven disc 25 during normal operation of the various switches, cams, etc., associated with the shaft 18, so that during the cyclic operation of the device the cam 20 and switch operation takes place in positive relation. When the pin 27 has engaged the arm or detent 39, however, subsequent rotation of the driving parts is resiliently decelerated by the frictional braking action of the washer 26. The washer 26 thus allows precision stopping of the control cam and switch combination precisely at the end of a complete revolution, and also acts as a brake to bring the driving motor and connected parts to rest in minimum time following the completion of an operating cycle. The latter function is advantageous in many applications, for instance, in the case of an automatic telephone answering and recording device, in which completion of one telephone recording may 35 be followed quickly by another.

From the foregoing it is evident that the apparatus described provides a precision one-revolution control device, without releasing clutches or similar complicated apparatus, while 40 at the same time providing means to brake the motor and driving parts to rest without shock at the conclusion of the operative cycle.

While the device has been set forth in preferred form and applied to a certain control combination for purposes of illustration, it will be understood that the invention is not limited to the exact apparatus and application described, as various modifications may be made without departing from the scope of the appended claims.

What is claimed is:

1. In a device of the character described, in combination, a rotary driving member, power means operatively connected to said driving member, said power means including means to accumulate a substantial momentum additive to that of said driving member, a rotary driven member, control means positively connected to said driven member, means between said members to frictionally transmit motion from said driving member to said driven member, and normally engaged means controllable by said control means to positively stop said driven member after a predetermined rotation of said driven member, said frictional member allowing limited rotation of said driving member subsequent to said stoppage of said driven member, means to energize said power means, and means controllable by said control means to de-energize said power means whereby said predetermined rotation is completed by said momentum.

2. In a recording device, in combination, a plurality of switches adapted to control operative functions of said device, a shaft, means on said shaft to actuate said switches in cyclic succession, 75 a motor, frictional driving means operatively dis-

posed between said motor and said shaft whereby said motor may drive said shaft and said actuating means throughout a predetermined rotative cycle, stop means to hold said shaft stationary against the urge of said frictional driving means in a predetermined rotative position of said shaft, electrical means to disable said stop means, and means to complete a circuit through one of said switches to said motor and a second circuit through another of said switches to said disabling means, said actuating means being adapted to open said second switch shortly after the start of said cycle and to open said first switch prior to completion of said cycle.

3. In a recording device, in combination, a 15 rotary driving member, a motor adapted to rotate said member, a rotary driven member, frictional driving means operatively disposed in permanent relation between said members, means to normally hold said driven member in a predetermined rotative position, electro-magnetic means to disable said holding means, a source of current, means to simultaneously energize said motor and said disabling means whereby said driven member may be rotated out of said predetermined position, means to de-energize said disabling means immediately after rotation of

5 said driven member out of said stop position, and means to de-energize said motor immediately prior to rotation of said driven member again into said stop position, the momentum of said motor operating through said driving means to complete rotation of said driven member into said stop position.

10 4. The combination claimed in claim 3 wherein said energizing means includes a relay and wherein said first and second de-energizing means include breakers operable by said driven member independently of said relay.
